UNITED STATES PATENT OFFICE

118,869

DESIGN FOR AN ANCHOR

Forrest L. Tower, Mendota, Ill.

Application November 7, 1939, Serial No. 88,119

Term of patent 14 years

To all whom it may concern:

Be it known that I, Forrest L. Tower, a citizen of the United States, residing at Mendota, in the county of La Salle and State of Illinois, have invented a new, original, and ornamental Design for an Anchor, of which the following is a specification, reference being had to the accompanying drawing, forming a part thereof.

In the drawing:

I claim:

The ornamental design for an anchor, as shown.

FORREST L. TOWER.
